PORTABLE ELECTRIC GREENHOUSE OR THE LIKE

Frederick W. Perl, Mansfield, and Louis J. De La Marter,
Lexington, Ohio, assignors to Westinghouse Electric
Corporation, a corporation of Pennsylvania

Filed Oct. 23, 1961, Ser. No. 67,262

Term of patent 14 years

(Cl. D35—3)

Fig. 1

Fig. 2

Fig. 3

FIG. 1 is a perspective view of a portable electric greenhouse embodying the new design;

FIG. 2 is a perspective view of a modification of the design for a portable electric greenhouse shown in FIG. 1; and

FIG. 3 is an elevational view of the side of the greenhouse shown at the left in FIG. 2.

The undisclosed side and end of the greenhouse are the same in appearance as the side and end disclosed.

The dominant features of our design are shown in full lines.

We claim:

The ornamental design for a portable electric greenhouse or the like, substantially as shown and described.
